UNITED STATES PATENT OFFICE.

ANTONIO CAPPABIANCA, OF BRADDOCK, PENNSYLVANIA.

MECHANICALLY-OPERATED CRIB.

Application filed January 31, 1923. Serial No. 616,216.

To all whom it may concern:

Be it known that I, ANTONIO CAPPABIANCA, a subject of the King of Italy, residing at Braddock, in the county of Allegheny and State of Pennsylvania, have invented certain new and useful Improvements in Mechanically-Operated Cribs, of which the following is a specification.

This invention relates to improvements in mechanically operated cribs.

An important object of the invention is to provide mechanical means for rocking a crib to eliminate the tiring manual performance of the same operation, and where-
15 by considerable time will be saved the attendant for performing other necessary duties.

A further object of the invention is the construction of efficient, durable mechanism
20 for performing the above mentioned opera-
tion.

Other objects and advantages of the in-
vention will be apparent during the course
of the following description.

25 In the accompanying drawing forming a part of this specification and in which like numerals are employed to designate like parts throughout the same,

Figure 1 is a top plan view with a portion
30 of the crib broken away to more clearly
show the mechanical operating means
carried by the crib supporting frame,

Figure 2 is a vertical sectional view taken
35 on line II—II of Fig. 1,

Figure 3 is a fragmentary vertical sec-
tional view taken on line III—III of
Fig. 1,

Figure 4 is a fragmentary vertical sec-
tional view taken on line IV—IV of
40 Fig. 1,

Figure 5 is a fragmentary vertical sec-
tional view taken on line V—V of Fig. 1,

Figure 6 is a fragmentary vertical sec-
tional view taken on line VI—VI of Fig.
45 1, and

Figure 7 is a detail sectional view show-
ing a portion of a resilient means employed
for returning the crib to a vertical position
after the rocking operation has stopped.

50 In the drawings, wherein for the purpose
of illustration is shown a preferred embodiment
of this invention, the numeral 1 designates a skeleton frame that is provided for
properly supporting the crib 2 and having
55 transverse brace bars 3, 4 and 5 for sup-
porting the operating mechanism to be de-

scribed hereafter. It is to be understood
that the crib 2 may be constructed in any
desired manner and provided with perpen-
dicular supporting rings or eyes 6 that are
60 carried by the opposite ends of the crib and
positioned centrally thereof for pivotally
engaging supporting pins 7 carried by the
opposite ends of the skeleton frame 1.

The operating mechanism employed for
rocking the crib 2 is supported, as stated
above, by the transverse brace bars 3, 4 and
5, and consists of a driven shaft 8 that is
suitably journaled in the bearing members
9 and 10 that are carried by the brace bars
70 3 and 4 respectively. This driven shaft 8
is provided with a pulley wheel 11 that is
rigidly secured to the end 12 and is further
provided with a pinion 13 that is positioned
75 centrally between the said brace bars 3 and 4.
There is further provided a relatively long
shaft 14 that extends longitudinally of the
skeleton frame 1 and is suitably journaled
in the bearing members 15, 16 and 17 carried
80 by the brace bars 3, 4 and 5 respectively.
This longitudinally extending shaft 14 is
positioned substantially upon a vertical
plane with the pivot pins 6 carried by the
skeleton frame 1 and is provided with a gear
85 18 that is positioned between the brace bars
3 and 4 and constantly in mesh with the
pinion 13 for affording operative connection
with the driven shaft 8. Referring partic-
ularly to Fig. 4, there is shown an eccentric
block 19 that is suitably keyed to the longi-
tudinal shaft 14 and is loosely engaged by
90 the split collar 20 that is secured thereto by
the clamping bolts 21, the split collar 20 is
provided with a boss 22 that is adapted for
receiving one end of a rod 23 threaded
95 therein. The outer end of this rod 23 is
pivotally connected, as at 24, to an arm 25
carried by the stub shaft 26. Referring to
Fig. 1, it will be seen that this shaft 26 is
suitably journaled, as at 27, to the trans-
verse brace bar 5 and is further provided
100 with an arm 28 that is rigidly connected to
the outer end of this shaft and best shown
in Fig. 6. Pivotally connected, as at 29, to
the upper end of the arm 28 is a link 30 that
is pivotally connected at its opposite end 31
105 to a lug 32 that is rigidly secured, as at 33,
to one of the bottom slats 34 carried by the
crib 2 and best shown in Fig. 1.

The means employed for returning the
crib to a vertical position, after the rock
mechanism has been shut off, is shown in de-

tail in Figs. 3, 5 and 7. Referring to Figs. 3 and 7 there is shown an eccentric block 35 that is suitably keyed to the longitudinal shaft 14 and is loosely engaged by the split 5 collar 36 that is retained in position by means of the clamping bolts 37, as shown. Secured to the upper edge of the split collar 36 is an eye member 38 that is connected to a coil spring 39 which extends to an eye 10 member 40 carried by one of the bottom slats of the crib 2. In Fig. 5 there is shown a collar or ring member 41 that is loosely mounted upon the end 42 of the longitudinal shaft 14 and is provided with an arm 43 that is 15 connected by the spring 44 and eye 45 with one of the bottom slats of the crib.

The driving power for operating this rocking mechanism embodies an electric motor 46 that is properly supported and secured to the transverse brace bars 3 and 4 20 and has an electric switch 47 for controlling the supply of current thereto. The armature shaft of the motor 46 is provided with a small pulley wheel 48 that is operatively connected to the pulley wheel 11 carried by the driven shaft 8, by the belt 49 as 25 shown.

The operation of the device is as follows:—

Upon turning on the current to the electric motor 46, the driven shaft 8 will be rotated by means of the belt 49 operatively connected with the pulley wheels 11 and 48, and the pinion 13 will drive the gear 18 for 30 rotating the longitudinal shaft 14. The rotation of this shaft 14 will impart movement to the rod 23, through the eccentric block 19 and split collar 20 for actuating the link 30 to cause the cradle 2 to rock upon the supporting pins 7 carried by the skeleton frame 1. Upon shutting off the current to the motor 46 the rocking of the cradle will naturally stop, the spring 44, carried by the arm 43, and the spring 39, carried by the 35 collar 36, will exert a pull upon the cradle 2, should it stop in other than a vertical position. This pull will be sufficient to operate the mechanism for allowing the cradle to be returned to its desired resting position.

It is to be understood that the form of this invention herewith shown and described is to be taken as a preferred example of the same, and that various changes in the shape, size, and arrangement of parts may be 40 sorted to without departing from the spirit of the invention or the scope of the subjoined claims.

Having thus described the invention, I claim:—

1. In a device of the class described a frame, a cradle pivotally carried by said frame, transverse brace bars carried by said

frame, a driven shaft carried by said brace bars, a longitudinal shaft carried by said brace bars and operatively connected to 65 said driven shaft, a connection between said longitudinal shaft and cradle for rocking the latter, and means carried by said brace bars for operating said driven shaft.

2. In a device of the class described a 70 frame, a cradle pivotally carried by said frame, transverse brace bars carried by said frame, a driven shaft carried by said brace bars, a longitudinal shaft carried by said brace bars and operatively connected to 75 said driven shaft, a connection between said longitudinal shaft and cradle for rocking the latter, means carried by said brace bars for operating said driven shaft, and means associated with said longitudinal shaft and cradle for returning the latter to a vertical 80 position after the rocking operation has been stopped.

3. In a device of the class described a 85 skeleton frame, a cradle pivotally carried by said frame, brace bars carried by said frame, a driven shaft carried by said brace bars, a longitudinal shaft carried by said brace bars and operatively connected to 90 said driven shaft, an eccentrically operated connection between said longitudinal shaft and cradle for rocking the latter, and means carried by said brace bars for rotating said driven shaft.

4. In a device of the class described a 95 skeleton frame, a cradle pivotally supported by said frame, brace bars carried by said frame, a driven shaft journaled to said brace bars, a longitudinal shaft journaled to said brace bars and operatively connected to 100 said brace bars and operatively connected to said driven shaft, an eccentric block keyed to the longitudinal shaft, a collar engaging said eccentric block, a connection between said collar and cradle for rocking the latter, and means carried by said brace bars for operating said driven shaft.

5. In a device of the class described a 110 skeleton frame, a cradle pivotally supported by said frame, brace bars carried by said frame, a driven shaft journaled to said brace bars, a longitudinal shaft journaled to said brace bars and operatively connected to 115 said driven shaft, an eccentric block keyed to the longitudinal shaft, a collar engaging said eccentric block, a connection between said collar and cradle for rocking the latter, means carried by said brace bars for operating said driven shaft, and resilient means for returning said cradle to a vertical position after the rocking operation 120 has been stopped.

In testimony whereof I affix my signature.

ANTONIO CAPPABIANCA.
